ATTYS.

UNITED STATES PATENT OFFICE.

RAY Y. CLIFF, OF SEBRING, OHIO, ASSIGNOR TO THE SAXON CHINA COMPANY, OF SEBRING, OHIO, A CORPORATION OF OHIO.

DESIGN FOR A MATCH-HOLDER AND ASH-TRAY.

54,242.

Specification for Design.

Patented Dec. 9, 1919.

Application filed July 17, 1919. Serial No. 311,650. Term of patent 7 years.

To all whom it may concern:

Be it known that I, RAY Y. CLIFF, a citizen of the United States, residing at Sebring, in the county of Mahoning and State of Ohio, have invented a new, original, and ornamental Design for a Match-Holder and Ash-Tray, of which the following is a specification, reference being had to the accompanying drawing, forming part thereof.

In the drawings:—the figure is a perspective view of the match holder and ash tray.

I claim:

The ornamental design of a match holder and ash tray, substantially as shown.

RAY Y. CLIFF.

Witnesses:

ROY WALKER,
CARL B. HAMILTON.
